(57) **CLAIM**

I claim the ornamental design for the earbud speaker for
cellular telephone, as shown and described.

DESCRIPTION

FIG. 1 is a top-left perspective view of the earbud speaker.
FIG. 2 is a front elevational view of the earbud speaker.
FIG. 3 is a bottom-right perspective view of the earbud
speaker.

FIG. 4 is right side view of the earbud speaker (the left side
view being identical to the left side view).

FIG. 5 is a rear view of the earbud speaker.

FIG. 6 is a top view of the earbud speaker; and,

FIG. 7 is a bottom view of the earbud speaker.

The broken lines in FIGS. 1, 2, 3, 4, 5, 7 are for illustrative
purposes only and forms no part of the claimed design.
